CONVERTIBLE STEP STOOL

Robert Goldman and Lillian Goldman, Louisville, Ky.,
assignors to Lili, Inc., Salem, Ind., a corporation of
Indiana

Filed Aug. 18, 1961, Ser. No. 66,411

Term of patent 3½ years

(Cl. D15—1)

Fig. 1.

Fig. 3.

Fig. 2.

Fig. 4.

FIGURE 1 is a perspective view of a convertible step stool showing our new design;

FIGURE 2 is a side elevational view on a reduced scale;

FIGURE 3 is a side elevational view of the stool of FIGURE 2 with the backrest pivoted to an alternate position; and

FIGURE 4 is a rear perspective view of the stool of FIGURE 2 with the backrest pivoted to the alternate position shown in FIG. 3.

The side of the device opposite the side shown in the drawing is a mirror image of the side which is shown.

We claim:

The ornamental design for a convertible step stool, as shown and described.
